United States Patent Office

Des. 193,514

Patented Sept. 4, 1962

193,514

TAPE RECORDER

Theodore S. Briskin and Sheldon Lee Pastor, Chicago, Ill., assignors, by mesne assignments, to Revere Camera Company (formerly Samica Corporation), a corporation of Delaware

Filed Mar. 3, 1960, Ser. No. 59,607

Term of patent 14 years

(Cl. D26—14)

The single FIGURE of the drawing is a perspective view of a tape recorder, showing our new design.

The essential features of the design are shown in full lines.

The rear of the tape recorder is conventional.

We claim:

The ornamental design for a tape recorder, as shown and described.
